UNITED STATES PATENT OFFICE.

MARY OLSHASKIE, OF PANA, ILLINOIS.

BAKE-PAN.

No. 902,904.

Specification of Letters Patent. Patented Nov. 3, 1908.

Application filed February 18, 1908. Serial No. 416,563.

To all whom it may concern:

Be it known that I, MARY OLSHASKIE, a citizen of the United States, residing at Pana, in the county of Christian and State 5 of Illinois, have invented certain new and useful Improvements in Bake-Pans, of which the following is a specification.

This invention relates to bake pans and has for an object to provide a pan which 10 will be simple in construction, inexpensive to manufacture and which will be adjustable to suit various occasions.

Other objects and advantages will be apparent from the following description and it 15 will be understood that changes in the specific structure shown and described may be made within the scope of the claims without departing from the spirit of the invention.

In the drawings forming a portion of this 20 specification, and in which like numerals of reference indicate similar parts in the several views, Figure 1 is a side elevational view of the present invention, Fig. 2 is a horizontal sectional view on the line 2—2 of Fig. 25 1, Fig. 3 is a transverse sectional view on the line 3—3 of Fig. 1, Fig. 4 is a vertical longitudinal sectional view.

Referring now more particularly to the drawings, there is shown a bake pan 10 comprising two slidable sections 11 and 12 respectively.

The section 12 comprises a bottom 13, sides 14 and 15 respectively, and an end 16. The sides 14 and 15 at their upper ends are 35 bent outwardly to provide flanges 16', as shown. Each of the sides 14 and 15 at their inner ends are stamped to form outwardly directed tongues 17 which are arranged to lie with their inner faces spaced from the 40 sides 14 and 15 for a purpose to be herein-after described.

The section 11 consists of a bottom 18, sides 19 and 20 respectively, and an end 21. The sides 19 and 20 have their upper ends or 45 edges bent outwardly at right angles as shown at 22 then downwardly as shown at 23 and then inwardly as shown at 24 to pro-

vide channels arranged to receive the flanges 16' of the section 12. The flanges 16' are preferably corrugated transversely as shown 50 at 16''. At the outer ends, each of the portions 24 are extended downwardly as shown at 26 to provide stops for engagement with the tongues 17, and are thus arranged to prevent displacement of the sections 11 and 12 55 respectively.

Each of the members 11 and 12 respectively at their ends are provided with handles 27. It will thus be seen that a simple, cheap and effective pan is provided which may be 60 conveniently adjusted to suit the occasion.

What is claimed is:

1. A pan of the class described comprising two sections, each section including a bottom, side walls and an end wall, the side 65 walls of one section being bent to form longitudinally extending channels, the side walls of the other section having corrugated flanges disposed for movement in said channels, tongues carried by one of said sections 70 and stops carried by the other of said sections for co-engagement with said tongues.

2. A pan section including a bottom, an end wall, and connecting side walls, said side walls having portions at their upper edges 75 bent to form longitudinally disposed channels, stops carried by the side walls, in combination with a pan section including a bottom, an end wall and connecting side walls, said side walls of the last named section having lateral flanges at their upper edges disposed for movement in the channels of the first named section, said flanges being corrugated transversely throughout their lengths, and tongues carried by the side walls of the 85 last named section for engagement with said stops when the sections are drawn apart to their greatest extent.

In testimony whereof I affix my signature, in presence of two witnesses.

MARY OLSHASKIE.
